CLAIM

The ornamental design for a bracket type luminaire, as shown and described.

DESCRIPTION

FIG. 1 is a top plan view of a bracket type luminaire, showing our design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top perspective view thereof;

FIG. 8 is a bottom perspective view thereof;

FIG. 9 is a top perspective view thereof in an alternate configuration; and,

FIG. 10 is a bottom perspective view thereof in an alternate configuration.

The broken line showing in the Figures represents portions of the bracket type luminaire that form no part of the claimed design.

1 Claim, 10 Drawing Sheets
